(57) **CLAIM**

The ornamental design for a sun blocking scarf having sleeve panels, as shown and described.

DESCRIPTION

FIG. 1 is a back perspective view of the sun blocking scarf having sleeve panels of the present invention;

FIG. 2 is a back view thereof;

FIG. 3 is a top view thereof;

FIG. 4 is a front view thereof;

FIG. 5 is a rear view thereof;

FIG. 6 is a left-side view thereof; and,

FIG. 7 is a right-side view thereof.

The broken lines represent stitching which forms part of the claimed design. The hashing only reflects fabric type material.
